Primary Examiner — Cathron C Brooks*Assistant Examiner* — Samantha Q. Lawrence(74) *Attorney, Agent, or Firm* — Workman Nydegger; Justin Cassell(57) **CLAIM**

The ornamental design for an orthopedic device, as shown and described.

DESCRIPTION

FIG. 1 is a perspective view of an orthopedic device.

FIG. 2 is a first side elevational view thereof.

FIG. 3 is a second side elevational thereof.

FIG. 4 is a top plan view thereof.

FIG. 5 is a bottom plan view thereof.

FIG. 6 is a front elevational view thereof; and,

FIG. 7 is a rear elevational view thereof.

The broken lines shown in FIGS. 1-7 illustrate portions of the orthopedic device that form no part of the claimed design.
